(57) **ABSTRACT**

The present invention is a pressure-controlled release dispenser. More particularly, the present invention relates to a blister pack with individual compartments that can contain a fluid, e.g., hand sanitizer, with a piercing mechanism within an individual compartment that enables pressure-controlled release of single use portions of the fluid contained therein. A blister pack of the present invention can also contain single use portions of dry flowable materials or solid materials.

DESCRIPTION OF THE DRAWINGS

The drawings constitute a part of this specification and include exemplary embodiments of the Wearable Pressure Controlled Release Dispenser Device and Method which may be embodied in various forms. It is to be understood that in some instances, various aspects of the invention may be shown exaggerated or enlarged to facilitate an understanding of the invention. Therefore the drawings may not be to scale.

FIG. 1A is a side view of an embodiment of the invention with a lanyard.

FIG. 1B is a front view of an embodiment of the invention with a lanyard.

FIG. 1C is another side view of an embodiment of the invention with a lanyard.

FIG. 2 is a perspective view of an embodiment of the invention with a lanyard.

FIG. 3A is a side view of an embodiment of a dispenser or blister pack of the present invention including perforated individual compartments.

FIG. 3B is a top view of the dispenser or blister pack as shown in FIG. 3A.

FIG. 3C is a side view of the of the dispenser or blister pack as shown in FIG. 3A.

FIG. 3D is another side view of the of the dispenser or blister pack as shown in FIG. 3A.

FIG. 3E shows a bottom view of the blister pack shown in FIG. 3A in which the base layer is shown with perforations.

FIG. 4A is a perspective view an embodiment of an individual compartment that can be included in one or more embodiments of a dispenser or blister pack of the present invention, showing the individual compartment open along a bottom portion, and including an arc shaped piercing member extending from one side of the compartment to another side of the compartment with the arc shaped piercing member of about uniform width with the side wall of the compartment.

FIG. 4B is a front view of the embodiment in FIG. 4A.

FIG. 4C is a partial detail view of a piercing member of the individual compartment as shown in FIG. 4A.

FIG. 4D is a side view of the embodiment in FIG. 4A.

FIG. 5A is a side view of an embodiment of a dispenser or blister pack of the present invention.

2

FIG. 5B is a front view of the dispenser or blister pack as shown in FIG. 5A.

FIG. 5C is a side view of a protective layer on the back of the dispenser or blister pack as shown in FIG. 5A.

FIG. 5D is a back view of the dispenser or blister pack as shown in FIG. 5A including a top layer without perforations.

FIG. 6A is a top view of the dispenser or blister pack showing a punched hole to insert a lanyard clip through.

FIG. 6B is a back view of FIG. 6A.

FIG. 6C shows one embodiment of a lanyard with a clip that can be inserted through the punched hole in FIG. 6A.

FIG. 7 is a perspective view of an embodiment of an individual compartment that can be used in one or more embodiments of a dispenser or blister pack including an arc shaped piercing member that extends from one side of the compartment to another side of the compartment wherein the sides of the piercing member within the compartment are of uniform thickness with the piercing arc member.

FIG. 8 is a perspective view of an embodiment of an

individual compartment that can be included in one or more embodiments of a dispenser or blister pack of the present invention including a shorter arc shaped piercing member that does not extend all the way from one side of the compartment to another side of the compartment.

FIG. 9A is another perspective view of the embodiment in FIG. 4A.

FIG. 9B is a side view of the embodiment in FIG. 4A.

FIG. 9C is a top view of the embodiment in FIG. 4A.

FIG. 9D is a side view of the embodiment in FIG. 4A, which shows the front profile of the piercing member.

FIG. 9E is a back view of the piercing member of FIG. 9D.

FIG. 9F is a side view of the piercing member of FIG. 9D.

FIG. 9G is a perspective view of an embodiment of an individual compartment that can be used with one or more embodiments of a dispenser or blister pack of the present invention, wherein the individual compartment includes two arc shaped piercing members within the individual compartment.

FIG. 10A is a perspective view of a sixth embodiment of an individual compartment that can be used in one or more embodiments of a dispenser or blister pack of the present invention that includes an oval-shaped piercing member within the individual compartment.

FIG. 10B is a side view of the compartment as shown in FIG. 10A.

FIG. 10C is a top view of the compartment as shown in FIG. 10A.

FIG. 10D is another side view of the compartment as shown in FIG. 10A.

FIG. 10E is a bottom view of the piercing member of the compartment as shown in FIG. 10A.

FIG. 10F is a side view of the piercing member of the compartment as shown in FIG. 10A.

FIG. 11A is a perspective view of an embodiment of an individual compartment that can be included in one or more embodiments of a dispenser or blister pack of the present invention that includes a T-shaped piercing member within the compartment.

FIG. 11B is a side view of the compartment as shown in FIG. 11A.

FIG. 11C is a top view of the compartment as shown in FIG. 11A.

FIG. 11D is another side view of the compartment as shown in FIG. 11A.

FIG. 11E is a bottom view of the piercing member of the compartment as shown in FIG. 11A.

FIG. 11F is a forward side view of the piercing member of the compartment as shown in FIG. 11A.

FIG. 12A is a perspective view of an embodiment of an individual compartment that can be included in one or more embodiments of a dispenser or blister pack of the present invention that includes a circular-shaped piercing member within the compartment.

FIG. 12B is a longitudinal side view of the compartment as shown in FIG. 12A.

FIG. 12C is a top view of the compartment as shown in FIG. 12A.

FIG. 12D is another side view of the compartment as shown in FIG. 12A.

FIG. 12E is a bottom view of the piercing member of the compartment as shown in FIG. 12A.

FIG. 12F is a forward side view of the piercing member of the compartment as shown in FIG. 12A.

FIG. 13A is a perspective view of an embodiment of an individual compartment that can be included in one or more embodiments of a dispenser or blister pack of the present invention that includes a linear shaped piercing member extending from one side wall longitudinally into the compartment.

FIG. 13B is a longitudinal side view of the compartment as shown in FIG. 13A.

FIG. 13C is a top view of the compartment as shown in FIG. 13A.

FIG. 13D is another side view of the compartment as shown in FIG. 13A.

FIG. 13E is a partial detail view of the piercing member as shown in FIG. 13A.

FIG. 13F is a side view of the piercing member of the compartment as shown in FIG. 13A.

FIG. 14A is a perspective view of an eleventh embodiment of an individual compartment that can be included in one or more embodiments of a dispenser or blister pack of the present invention that includes two linear shaped piercing members, each extending from a side of the compartment longitudinally within the compartment.

FIG. 14B is a side view of the compartment as shown in FIG. 14A.

FIG. 14C is another side view of the compartment as shown in FIG. 14A.

FIG. 14D is a partial detail view of one of the piercing members of the compartment as shown in FIG. 14A.

FIG. 14E is a side view of one of the piercing members of the compartment as shown in FIG. 14A.

FIG. 14F is a top view of the compartment as shown in FIG. 14A.

FIG. 15A is a perspective view of an embodiment of an individual compartment that can be included in one or more embodiments of a dispenser or blister pack of the present invention wherein the compartment is circular and includes a linear shaped piercing member extending laterally across the compartment from one side of the compartment to another side of the compartment.

FIG. 15B is a longitudinal side view of the compartment as shown in FIG. 15A.

FIG. 15C is a top view of the compartment as shown in FIG. 15A.

FIG. 15D is another side view of the compartment as shown in FIG. 15A.

FIG. 15E is a partial detail view of the piercing member of the compartment as shown in FIG. 15A.

FIG. 15F is a side view of the piercing member of the compartment as shown in FIG. 15A.

FIG. 16A is a perspective view of an embodiment of an individual compartment that can be included in one or more embodiments of a dispenser or blister pack of the present invention wherein the compartment is circular and includes a circular shaped piercing member.

FIG. 16B is a longitudinal side view of the compartment as shown in FIG. 16A.

FIG. 16C is a top view of the compartment as shown in FIG. 16A.

FIG. 16D is another side view of the compartment as shown in FIG. 16A.

FIG. 16E is a bottom view of the piercing member as shown in FIG. 16A.

FIG. 16F is a side view of the piercing member of the compartment as shown in FIG. 16A.

FIG. 17A is a side view of an embodiment of an individual compartment that can be included in one or more embodiments of a dispenser or blister pack of the present invention wherein the compartment includes a circular shaped piercing member.

FIG. 17B is a prospective view of the compartment in FIG. 17A.

FIG. 18A is a side view of an embodiment of an individual compartment that can be included in one or more embodiments of a dispenser or blister pack of the present invention wherein the compartment includes a circular shaped piercing member where the piercing member does not span the entire length of the depth of the compartment.

FIG. 18B is a perspective view of the compartment in FIG. 17A.

FIG. 19A is a perspective view of an embodiment of an individual compartment that can be included in one or more embodiments of a dispenser or blister pack of the present invention wherein the compartment comprises a slit through which liquid can flow.

FIG. 19B is a side view of a dispenser or blister pack with the compartment of FIG. 19A.

FIG. 19C is a top view of a dispenser or blister pack with the compartment of FIG. 19A.

FIG. 19D is another side view of a dispenser or blister pack with the compartment of FIG. 19A, which shows a detail of the piercing member.

FIG. 20A is a side view of an embodiment of an individual compartment that can be included in one or more embodiments of a dispenser or blister pack of the present invention wherein the compartment comprises a slit through which liquid can flow and wherein the piercing member is circular.

FIG. 20B is a top view of a dispenser or blister pack with the compartment of FIG. 20A.

FIG. 20C is a side view of a dispenser or blister pack with the compartment of FIG. 20A.

FIG. 20D is another side view of a dispenser or blister pack with the compartment of FIG. 20A, which shows a detail of the piercing member.

FIG. 21A is a perspective view of an embodiment of an individual compartment that can be included in one or more embodiments of a dispenser or blister pack of the present invention wherein the compartment comprises a slit through which liquid can flow and wherein the blister pack or dispenser comprises a center raised console opposite the top of the compartments.

FIG. 21B is a side view of a dispenser or blister pack with the compartment of FIG. 21A.

FIG. 21C is a top view of a dispenser or blister pack with the compartment of FIG. 21A.

FIG. 21D is another side view of a dispenser or blister pack with the compartment of FIG. 21A, which shows a detail of the piercing member.

BACKGROUND

There is a need in the art for a dispenser that is wearable by a user, and which can dispense single use portions of desired products that is a liquid, gel, or flowable solid, for a user.

Blister packs are known in the art for packaging solid materials, for instance, pills. However, any prior art blister pack is not effective at housing and dispensing liquids. This is because, the foil or covering that closes a typical blister is completely removed by the user to access to the solid contents. If a user were to attempt to remove a covering on a typical blister pack that contained liquid in the conventional manner, all of the liquid would undoubtedly spill out of the blister in the process.

Accordingly, there is a need in the art for a blister pack or dispenser that can effectively release single use portions of liquids or fluids for a variety of purposes including, single use hand sanitizing treatments, liquid or powdered medication, sunscreen, insect repellent, lotion or liquid makeup.

There is also a need in the art for a blister pack or dispenser that can effectively release single use portions of dry flowable materials, e.g., powdered medication or powdered sport drink mix and/or single use portions of more than one type of product or composition, e.g., epoxy resin and hardening agent. For similar reasons stated above for why current blister packs are inadequate for storing and dispensing liquids, storing and dispensing a powder or gel-like substance is technically infeasible using the prior art systems.

The apparatus and method of the present invention solves the problems confronted in the art in a simple and straightforward manner. Claimed herein is a dispenser, which can be a blister pack, with a pressure-controlled release mechanism in individual compartments that allows a user to dispense single use portions of a fluid or liquid (e.g., to sanitize the user's hands at any time and any place), or flowable dry materials (e.g., powdered medication). The pressure-controlled release mechanism is a piercing mechanism that is fixed within individual compartments of the dispenser or blister pack.

In embodiments that include hand sanitizer, these embodiments can help prevent the spread of bacteria and viruses that can easily spread from person to person. This can be part of a standard operating procedure for businesses to provide a dispenser or blister pack of the present invention to employees and/or customers for businesses that are looking to move forward in the current COVID-19 pandemic environment. Being able to put hand sanitizer in a packet and give it to customers to wear on their body will let others know how serious the company is about protecting the health and wellbeing of each customer.

In one or more embodiments, a dispenser or blister pack of the present invention can include more than one compartment with more than one type of product or composition that is kept separate in the individual compartments and with each compartment and product ready to use. In this embodiment, for example, one compartment can have an epoxy resin and another compartment can have a hardener. When opened and applied together, a complete epoxy can be obtained. This embodiment can also be used for medications that need to be separated before use and which can be given in exact specified amounts to ensure compliance.

In one or more embodiments, a blister pack of the present invention can be used to advertise. In these embodiments, preferably a blister pack is not perforated. An example of this is for blister packs containing hand sanitizer for use at football games. A team could easily buy custom packs with advertising to give out to fans at games to wear while in the stadium. Additionally, the cost of the sanitizer and enhanced blister pack could be reduced by advertising by other entities like law firms or businesses that wish to sponsor the team.

10 Places and businesses that can potentially benefit from this embodiment are: airlines, cruise lines, trains, ferries, tour busses, long haul busses, casinos, amusement parks, museums, water parks, aquariums, zoos, professional sports teams, college sports teams, state fairs, festivals, concerts, conventions, resorts theaters and courtrooms.

In one or more embodiments, a dispenser or blister pack of the present invention can be filled with liquids or fluids or another desired material that is not hard enough on its own to break through the backing of the blister pack.

20 In one or more embodiments, a hole or opening is included along one end of a dispenser or blister pack, e.g., at a top portion of the pack, in an area that does not interfere with an individual compartment. A lanyard, tie, cord, or necklace of any kind can be inserted through the opening and tied to the pack and placed around a user's neck for easy use and accessibility. In other embodiments, a key ring or clip can be inserted through the opening for attaching the dispenser or blister pack on a user's clothing or a bag for example. This offers an improvement over the prior art for carrying, for example, hand sanitizer, which allows the materials to be at the user's finger tips rather than in a bag or storage area.

25 In one or more embodiments, a dispenser or blister pack is disposable with single use compartments. If hand sanitizer is included in the individual compartments, for example, this is beneficial given that the disposable dispensers of sanitizer can only be opened and used once and cannot be refilled with a cheaper or inferior solution.

30 In one or more embodiments, a larger sized compartment can hold contents for multiple uses. In one or more embodiments, a larger sized compartment with multiple chambers can hold contents for multiple uses, wherein each chamber can include a piercing member.

35 In one or more embodiments, a dispenser or blister pack can be filled with an exact amount of liquid or material allowed by the Federal Aviation Administration (FAA) to board a plane.

40 This invention offers many other improvements over the prior art, including, elimination of waste; reduction in manufacturing cost; and ease of use.

45 In one or more embodiments, a dispenser or blister pack of the present invention can be made without any perforations (depending on the desired application) so it can remain as one unit which can help to reduce litter. This embodiment can also help prevent blister packs or blister pack compartments from being a choking hazard. Being one whole unit can also help with custom advertising on packets.

50 In one or more embodiments, a dispenser or blister pack of the present invention includes a piercing plate or piercing member. Potential uses of a blister pack with piercing plate or piercing member include: 1) hand sanitizer; 2) liquid prescription medications; 3) powdered prescription; 4) medications; 5) perfumes; 6) moisturizers/lotions; 7) soaps; 8) insect repellent; 9) hobby paint; 10) glue; 11) sunscreen; 12) alcohol; 13) liquid or powdered vitamins; 14) cannabis tinctures; 15) powders; 16) granules; 17) soft gel capsules; 18) herbs or spices (e.g., in small amounts for meal planning

services); 19) cooling extracts or oils; 20) gum; 21) seeds; 22) dog or cat treats; 23) ointments or creams; and/or 24) single use makeups or testers for makeup counters.

As can be seen, a dispenser or blister pack of the present invention can be used for numerous desired applications.

DETAILED DESCRIPTION

The subject matter of the present invention is described with specificity herein to meet statutory requirements. However, the description itself is not intended to necessarily limit the scope of claims. Rather, the claimed subject matter might be embodied in other ways to include different steps or combinations of steps similar to the ones described in this document, in conjunction with other present or future technologies.

Turning to the figures, one or more embodiments of a dispenser of the present invention can resemble what is commonly referred to as a blister pack, which typically in the prior art contains compartments that house a pill or a vitamin. A prior art blister pack may have a foil base layer, for example, that a pill or vitamin can easily be pushed through when a user wishes to consume the pill or vitamin. As discussed, however, it has been considered impossible in the prior art to house a liquid in a blister pack.

Dispensers or blister packs 1 of the present invention include one or more piercing members 2, 201, 301, 401, 501, 601, 701, 801, 901, 202, 302, 402, 502 in individual compartments, and the piercing members enable the blister packs 1 to house a liquid in individual compartments 5, 501, 503 because without a piercing member, any product that is not hard enough to push out on its own would just smash or crush the plastic with no product coming out, or it would explode out of the packaging with product splashing everywhere. With the piercing member the amount of pressure put on the piercing member would control the opening of the back of the pack 1 thus allowing a controlled flow of the product. Various embodiments of piercing members are shown in the figures and labeled as 2, 201, 301, 401, 501, 601, 701, 801, 901, 202, 302, 402, 502.

In one or more embodiments, the piercing member has a continuous piercing member side wall with a periphery. A first fluid may be contained within the periphery of the continuous piercing member side wall and a second fluid can be contained within the compartment outside of the periphery of the continuous piercing member side wall.

A dispenser or blister pack 1 as shown in FIGS. 3B, 5B, 19C, 20B, 21C, for example, includes a plurality of individual compartments 5, 501, 503 that preferably can hold a single use portion of a desired material, e.g., a fluid or dry flowable material. The individual compartments 5, 501, 503 of a dispenser or blister pack 1 have a shape resembling a rectangle with rounded corners and/or surfaces 5 or as a circle 501.

In one or more embodiments, a dispenser or blister pack 1 also includes a plurality of individual compartments 5, 501, 503 that preferably can hold a single use portion of a desired material, e.g., a fluid, gel, or dry flowable material.

The individual compartments 501 of a dispenser or blister pack as shown in FIGS. 15A-15D have a circular shape or an at least substantially circular shape. Although not shown, individual compartments of a dispenser or blister pack of the present invention can also have other desired shapes, e.g., square, rectangular, irregular rectangular or square, oval, etc.

A dispenser or blister pack 1 can have any desired number of individual compartments 5, 501, 503, e.g., 1, 2, 3, 4, 5, 6, 7, 8, 9, 10, 11, 12, 13, 14, 15, 16, 17, 18, 19, 20 or more

individual compartments 5, 501, 503. Preferably a dispenser or blister pack 1 is of size that can easily be coupled to a lanyard 3 or other necklace, e.g., through an opening on the blister pack 1 in an area that is not part of a containment area 5 of an individual compartment 5, 501, 503, and preferably a dispenser or blister pack 1 is of a size that can conveniently be worn by a user. A blister pack 1 can also be coupled to a clip or key chain, for example, that can be coupled to a user's clothing, or to a purse or backpack or other desired bag. For example, FIGS. 6A and 6B show a blister pack 1 with a whole punched 12 through which a clip 301 such as the one shown in FIG. 6C can pass through to secure the blister pack 1.

As shown in, for example, FIGS. 4A and 4B, an individual compartment 5 has a continuous side wall 9, a top portion 10 and an open area or space 7 between the side wall 9 and top portion 10 that can house a material, e.g., a fluid, gel, or dry flowable material. The blister pack 1 may also have a base layer 6, that extends across the individual compartment 5 bottom opening and may extend as a single sheet across the entire blister pack 1 in order to close the compartment and keep the liquid inside. The base layer 6 may also have perforations 15 as shown in FIG. 3E, which facilitate removal of the base layer 6 when desired.

A compartment 5, 501, 503 can have a depth of 2 to 10 mm, and preferably more or less depending on the application. Preferably there is about 0 to 10 millimeters between a piercing edge of the piercing member (e.g., as shown in FIG. 4A, 4B, element 2) and the base layer 6. More preferably, there is approximately 2-10 millimeters between a piercing edge of the piercing member 2 and the base layer 6. The piercing member 2 can touch the base layer 6 or foil of the lidding material, but it is preferably in most applications for the piercing member 2 to be sized so as not to touch the base layer 6, unless specific pressure is applied, in order to prevent accidental discharge.

In one or more embodiments, the materials used to construct the piercing member and side wall (known as the forming film) can be PVC, polypropylene (PP), polyester (PET), Polyvinylidene chloride (PVDC), PVC/chlorotrifluoroethylene (CTFE), Oriented polyamide (OPA)/aluminum/PVC or nylon/aluminum/PVC, or CTFE homopolymer.

A top layer of material 11, e.g., made of aluminum, paper 45 and aluminum, or paper, PVC, and aluminum can be located on top of the base layer 6 to provide further protection for the blister pack 1. The top layer 11 may be removably attached by peeling. Top layer 11 is preferably coupled to base layer 6 with adhesive, which enables easy removal of this top, protective layer 11. Top layer 11 can prevent inadvertent puncturing or breaking of base layer 6 until it is desired to do so. Protective layer 11 can also be included as a child safety feature.

The top layer 11 may also cover the opposite side of the blister pack 1. In that embodiment, top layer perforations, for example, 4 and 4a in FIG. 3B can be included in both the lower top layer 11 and upper top layer, so as to easily be able to separate or remove individual compartments 5, 501, 503 if desired.

The top layer of material 11 preferably completely covers base layer 6 of dispenser or blister pack 1 and closes each compartment 5, 501, 503 so that a desired material can be contained therein. Preferably base layer 6 and top layer 11 are made of a material that can be pierced or broken by a piercing member 2, 201, 301, 401, 501, 601, 701, 801, 901, 202, 302, 402, 502 when it is desired to release a material contained within compartment 5, 501, 503. Preferably mate-

rial held within a compartment **5**, **501**, **503** will not pierce or break base layer **6** or top layer **11** on its own.

Base layer **6** and top layer **11** may be aluminum, paper and aluminum, or paper, PVC, and aluminum. In other embodiments, any suitable material known in the art may be used.

FIGS. 3A-3D illustrate an embodiment of an individual compartment **5** that can be included in a dispenser or blister pack **1** of the present invention, with an arc shaped piercing member **2** wherein the arc shaped piercing member **2** extends from one side of the compartment **5** to another side of the compartment **5** and is narrower than the side wall **9** of the compartment **5**. Piercing member **2** can be integrally formed with side wall **9** and top portion **10** of compartment **5**. A single piece construction is a preferable manner in which to produce the piercing member **2** and side wall construction.

In another embodiment, the piercing member **2** and side wall can be produced by affixing the piercing mechanism preferably with a non-reactive adhesive. Affixing a piercing mechanism by using an adhesive or some other potentially removable mechanism can result in a choking hazard that a single piece construction avoids. This style compartment is to house any and all types of fluids, gels, or dry flowable materials.

FIGS. 4A-4D; 7 illustrate a second embodiment of an individual compartment that can be included in one or more embodiments of a dispenser or blister pack **1** of the present invention, showing the individual compartment **5** open along a bottom or back side, and including an arc shaped piercing member **2** extending from one side of the compartment to another side of the compartment with the arc shaped piercing member **2** having a width that is about uniform with a width of the side walls **9** of the compartment **5**. Piercing member **2** can be integrally formed with side wall **9** and top portion **10** of compartment **5** as described above. This style compartment is to house any and all types of fluids, gels, or dry flowable materials.

FIGS. 9A-9F, 8 illustrates an embodiment of an individual compartment **5** that can be included in one or more embodiments of a dispenser or blister pack **1** of the present invention including a shorter arc shaped piercing member **301** that does not extend all the way from one side of the compartment to another side of the compartment. Piercing member **301** can be integrally formed with side wall **9** and top portion **10** of compartment **5**, or just integrally formed with top portion **10** as described above. This style compartment is to house any and all types of fluids, gels, or dry flowable materials.

FIG. 9G illustrates an embodiment of an individual compartment **5** that can be used with one or more embodiments of a dispenser or blister pack **1** of the present invention that includes two arc shaped piercing members **301** within the individual compartment **5**. Although pictured as arc piercing member **301** in shape and size, the shaped piercing members **301** can be a piercing member shaped in any manner described herein. Each piercing member **301** can be integrally formed with side wall **9** and top portion **10** of compartment **5**, integrally formed with top portion **10** as described above. This style compartment is to house any and all types of fluids, gels, or dry flowable materials.

FIGS. 10A-10F illustrate an embodiment of an individual compartment **5** that can be used in one or more embodiments of a dispenser or blister pack **1** of the present invention that includes an oval-shaped piercing member **401** within the individual compartment **5**. Piercing member **401** can be integrally formed with a top portion **10** of compartment **5** as

described above. This style compartment is to house any and all types of fluids, gels, or dry flowable materials.

FIGS. 11A-11F illustrate an embodiment of a compartment **5** that can be included in one or more embodiments of a dispenser or blister pack **1** of the present invention that includes a t-shaped piercing member **501** within the compartment **5**. Piercing member **501** can be integrally formed with a top portion **10** and side wall **9** of compartment **5** as described above. This style compartment is to house any and all types of fluids, gels, or dry flowable materials.

FIGS. 12A-12F illustrate an embodiment of a compartment **5** that can be included in one or more embodiments of a dispenser or blister pack **1** of the present invention that includes a circular-shaped piercing member **601** within the compartment **5**. Piercing member **601** can be integrally formed with a top portion **10** of compartment **5** as described above. This style compartment is to house any and all types of fluids, gels, or dry flowable materials.

FIGS. 13A-13F illustrate an embodiment of a compartment **5** that can be included in one or more embodiments of a dispenser or blister pack **1** of the present invention that includes a linear shaped piercing member **701** extending from side wall **9** a distance longitudinally into the open area or space **19** of compartment **5**. Piercing member **701** can be integrally formed with a top portion **10** and side wall **9** of compartment **5**, integrally formed with top portion **10** as described above. This style compartment is to house any and all types of fluids, gels, or dry flowable materials.

FIGS. 14A-14F illustrate an embodiment of a compartment **5** that can be included in one or more embodiments of a dispenser or blister pack **1** of the present invention that includes two linear shaped piercing members **801a**, **801b**, each extending from one side of the compartment longitudinally into open area or space **19** within the compartment **5**. The piercing members **801a**, **801b** can be integrally formed with a top portion **10** and side wall **9** of compartment **5**, integrally formed with a top portion **14** as described above. This style compartment is to house any and all types of fluids, gels, or dry flowable materials.

FIGS. 15A-15F illustrate an embodiment of a compartment **501** that can be included in one or more embodiments of a dispenser or blister pack **1** of the present invention wherein the compartment **501** is circular and includes a linear shaped piercing member **901** extending laterally across the compartment **501** from one side of the compartment **501** to another side of the compartment. The piercing member **901** can be integrally formed with a top portion **10** and side wall **9** of compartment **5** as described above.

FIGS. 16A-16F illustrate an embodiment of a compartment **501** that can be included in one or more embodiments of a dispenser or blister pack **1** of the present invention wherein the compartment **501** is circular and includes a circular shaped piercing member **202**. The piercing member **202** can be integrally formed with a top portion **10** of compartment **501** as described above.

FIGS. 17A, 17B illustrate an embodiment of a compartment **5** that can be included in one or more embodiments of a dispenser or blister pack **1** of the present invention wherein the compartment **5** includes a circular shaped piercing member **302** where the piercing member spans the entire length of the depth of the compartment **5**. The piercing member **302** can be integrally formed with a top portion **10** of compartment **5** as described above.

FIGS. 18A, 18B illustrate an embodiment of a compartment **5** that can be included in one or more embodiments of a dispenser or blister pack **1** of the present invention wherein the compartment **5** includes a circular shaped piercing

11

member 402 where the piercing member does not span the entire length of the depth of the compartment 5. The piercing member 402 can be integrally formed with a top portion 10 of compartment 5 as described above.

FIGS. 19A-19D illustrate an embodiment of compartment 503 that can be included in one or more embodiments of a dispenser or blister pack 1 of the present invention wherein the compartment 503 is elongated and pill-shaped. The compartment 503 further comprises a slit compartment 13 which is in communication with the piercing member 502. As shown in FIGS. 19A-D, the piercing member 502 is a longitudinal fin shape. When the pressure is applied and the piercing member 502 is activated, it creates an opening in the slit compartment only so that fluid or fluid like materials flow only there the slit compartment 13.

FIGS. 20A-20D illustrate a similar embodiment to that of 19A-19D, except that the compartment 501 is square with rounded edges and the piercing member 602 is shaped like an arc.

FIGS. 21A-21D illustrate an embodiment similar to that of FIGS. 19A-19D, except that the blister pack or dispenser 1 further comprises a center raised console 14 opposite the top of the compartments.

As can be seen from the drawings, a wide variety of different types of piercing members 2 (or piercing plates) can be included in individual compartments 5, 501, 503 of a dispenser or blister pack 1 of the present invention. Other desired shapes and sizes of piercing plates or piercing members (e.g., 2) can also be included in a compartment 5, 501, 503. A piercing member (e.g., 2) can be integrally formed with some part of an individual compartment 5, 501, 503, e.g., so that it is fixed within a compartment 5, 501, 503 and extends into open area or space 7 of a compartment 5, 501, 503 from a top portion 10 or a side wall 9, or from both a top portion 10 or a side wall 9. Preferably a piercing member (e.g., 2) is of a size, shape and material that allows it to pierce or break through a base layer 6 when pressure is applied to base layer 6 in an area over the piercing member 2.

For the purpose of understanding the Wearable Pressure Controlled Release Dispenser, references are made in the text to exemplary embodiments of a Wearable Pressure Controlled Release Dispenser, only some of which are described herein. It should be understood that no limitations on the scope of the invention are intended by describing these exemplary embodiments. One of ordinary skill in the art will readily appreciate that alternate but functionally equivalent components, materials, designs, and equipment may be used. The inclusion of additional elements may be deemed readily apparent and obvious to one of ordinary skill in the art. Specific elements disclosed herein are not to be interpreted as limiting, but rather as a basis for the claims and as a representative basis for teaching one of ordinary skill in the art to employ the present invention.

The invention claimed is:

1. A dispenser comprising:

a. at least one compartment having a continuous side wall, a top portion, a piercing member fixed within said compartment, wherein the compartment is adapted to

12

house a fluid, gel, or dry flowable material in at least a portion of the space between said side wall and said top portion;

b. a base layer of material that defines a bottom portion of said compartment and prevents the fluid from exiting said compartment until said base layer is broken or pierced; wherein when pressure is applied to said base layer in an area over the piercing member, said piercing member pierces said base layer creating an opening in the base layer to access said fluid within said compartment.

2. The dispenser of claim 1 wherein said piercing member has an arc shape.

3. The dispenser of claim 1 wherein said piercing member has a T-shape, an oval shape, linear shape, or a circular shape.

4. The dispenser of claim 1 wherein said piercing member is formed integrally with said top portion of said compartment and extends partially into said compartment.

5. The dispenser of claim 1 wherein said piercing member is formed integrally with said side wall and said top portion of said compartment and extends at least partially laterally across said compartment.

6. The dispenser of claim 1 comprising a plurality of compartments.

7. The dispenser of claim 6 wherein each of said plurality of compartments house a single use application of the fluid.

8. The dispenser of claim 6 wherein each said plurality of compartments is attached to at least one other said compartment such that said fluid in each compartment cannot migrate to another said compartment and wherein each of said plurality of compartments comprises perforations around a periphery of each compartment.

9. The dispenser of claim 1 further comprising a top layer of material that requires more force to pierce than said base layer.

10. The dispenser of claim 1 wherein the piercing member has a continuous piercing member side wall with a periphery, and wherein a first fluid is contained within the periphery of the continuous piercing member side wall and wherein a second fluid is contained within the compartment outside of the periphery of the continuous piercing member side wall.

11. A dispenser comprising a plurality of individual compartments, each compartment comprising a continuous side wall, a top portion, a base layer, and a piercing member; wherein said top portion and said continuous side wall are integrated so as to form a hollow opening; wherein said piercing member is located within said hollow opening so as to be near said base layer but not in contact with said base layer; wherein each of said plurality of compartments is adapted to hold an individual dose of liquid or gel; wherein said individual dose is accessed by external pressure applied to said base layer at the approximate location of said piercing member; and wherein said plurality of said individual compartments are connected through a top layer, wherein said top layer comprises perforations which allow said plurality of individual compartments to be separated from one another without releasing said liquid or gel.
